UNITED STATES PATENT OFFICE.

PHILIP CORBIN AND ERNEST L. TEICH, OF NEW BRITAIN, CONNECTICUT; SAID
TEICH ASSIGNOR TO SAID CORBIN.

LOCK.

1,010,727.

Specification of Letters Patent.

Patented Dec. 5, 1911.

Application filed April 7, 1911. Serial No. 619,467.

To all whom it may concern:

Be it known that we, PHILIP CORBIN and ERNEST L. TEICH, citizens of the United States, residing at New Britain, county of 5 Hartford, State of Connecticut, have invented certain new and useful Improvements in Locks, of which the following is a full, clear, and exact description.

Our invention relates to improvements in 10 locks.

The object of the invention is to provide an exceedingly simple, compact and self-contained locking apparatus which may be readily applied to any latch of the usual 15 spindle operated type in such a manner that, without change or mutilation of the door carrying such latch, our improvement may be substituted for the ordinary outside knob spindle. In this connection the invention 20 is of particular utility as applied to the door of a closed carriage, such as a limousine, since it furnishes an effective means for locking the door. This and other advantages 25 will appear to the mechanic skilled in the art from a reading of the following description and an examination of the accompanying drawings, in which—

Figure 1 is an edge view of a part of a door equipped with a spring latch bolt and 30 furnished with our improved locking mechanism. Fig. 2 is a front elevation thereof. Fig. 3 is a central longitudinal section of our improved locking mechanism detached from the latch mechanism. Fig. 4 is a plan 35 view of said locking mechanism. Fig. 5 is a sectional view of certain parts taken on the line $x-x$, Fig. 1, and looking in the direction of the arrow. Fig. 6 is a view of the inside of the escutcheon. Fig. 7 illustrates a detail of construction. Fig. 8 is a 40 view of the outer end of the knob shank section detached. Fig. 9 is a view of the inner end of the handle section detached.

1 represents a door. 45 2 represents the usual spring latch bolt which may be mortised into the edge of the door in the usual manner. The latch mechanism includes the usual roll-back (not shown), which may be turned by the usual 50 spindle, such as 3.

4 represents the outside knob, the same being connected with the spindle 3 as hereinafter described, and in such manner that when the knob is turned, the spindle will 55 be turned and the latch 2 retracted. Obvi-

ously, if the spindle is locked against being turned, the latch cannot be operated, and hence the door will be locked.

Our invention aims at providing a simple locking apparatus by which any one outside 60 of the door may very easily lock the spindle actuated by the outer knob for the purpose intended.

In the particular form shown in the drawings, 5 represents an inside knob which, in 65 this instance, may be connected directly to the inner end of the spindle 3, although, obviously, any wellknown independent connection may be made between the latch bolt and the inside knob so that said latch may 70 be operated from the inside whether or not the outer knob is free.

Since our invention relates solely to the construction of the outer knob and the method of locking the same, the detailed 75 description herein will be confined thereto.

The knob 4 may be of any suitable design, the one shown in the drawings being the usual conventional design for doors such as employed in carriages. The handle portion of the knob is provided with a central hub 6, suitably designed and hollowed out 80 to receive a cylinder lock 7. This hub portion of the knob is made in two sections, namely, the lock receiving section 6 and the 85 shank section 8. The shank section is arranged to be detachably secured to the inner end of the section 6 by screws 9—9.

10 is a hollow knob shank rigidly connected with the section 8 and projecting forwardly and carrying at its inner end the knob spindle 3, whereby, when the shank 90 is turned, said spindle will be turned.

11 is an escutcheon arranged to be secured to the outside of the door. The escutcheon 95 has an outside bearing sleeve 12, and at its inner side is constructed in any suitable way to furnish two locking notches 13—13. In this instance, these locking notches are provided by slotting an inward sleeve-like extension, clearly shown in Figs. 3, 4 and 6. The cylinder lock is provided with the usual plug 14, the inner end of which is seen in Fig. 3.

15 is what we will term a plug extension. 105 This plug extension is connected to the inner end of the cylinder lock plug by a spiral 16. The knob shank 10 is provided with a longitudinal slot or slots 17.

18 is a pin carried by the plug extension 110.

15, the ends of said pin standing in and movable to and fro in the slot 17. The locking notches 13—13 are of suitable size to receive the pin ends which project slightly 5 above and below the surface of the knob shank, as shown in Fig. 3. When the door is unlocked, the pin 18 will stand in the position shown in Fig. 3, wherein it will be seen to be projected into such a plane that it 10 is entirely removed from the notches 13—13. When it is desired to lock the door, the cylinder lock plug 14 is turned by the use of a suitable key. As shown in the drawings, when this plug is turned clock-wise, it 15 will draw the plug extension outwardly, that is, in such a direction as to draw the pin 18 into the locking notches 13—13 at the inner side of the fixed escutcheon, hence, when said pin stands in said position, the outer 20 knob cannot be turned, for, as will be seen, the knob and knob shank being bound together, it follows that the knob shank being locked by reason of the pin 18, the knob is likewise locked.

25 In the preferred construction, and as seen in Fig. 5, the outer sleeve 12 of the escutcheon overstands the ends of the screws 9—9 when the parts are assembled, hence, it is impossible to remove the screws and separate 30 the mechanism. Again, in applying such a lock, it is important to secure the escutcheon against removal, and to that end said escutcheon should preferably be secured to the door by through bolts, or equivalent devices, as distinguished from mere 35 wood screws, although it is obvious that wood screws would be entirely effective since they furnish one secure means of holding the escutcheon against turning, and that is 40 all that is required so far as concerns the locking of the door.

We have added a further improvement which is preferably provided to prevent jamming the lock. This improvement comprises a device for limiting the degree of 45 turning movement of the plug. This is best seen in Figs. 3, 8 and 9, in which 19 represents a C-shaped piece located in a cavity in the shank section 8 of the knob hub and 50 loosely surrounding the spindle 3. This C-shaped piece 19 carries a stop pin 20.

21 is a fixed stop pin carried by the piece 8 and standing between the ends of the C-shaped member whereby it will be seen that 55 the C-shaped member may be given a partial oscillation in either direction to a degree limited by the space between the ends of said C-shaped member.

22 is a stop pin on the plug 14. This stop 60 pin 22 moves in a plane which will cause it to encounter the stop pin 20 on the C-shaped member. These parts are so arranged that the plug can be turned exactly one complete revolution in either direction 65 by means of a suitable key, the purpose be-

ing to prevent said plug from being turned to such a degree in either direction as to either injure or jam the spiral. In other words, it permits the plug to be turned one complete revolution so as to bring the key-hole into a proper position to permit the withdrawal of the key.

We have shown herein a preferred form of our invention, it being obvious that many changes can be made without departing 75 from the spirit or scope of the invention.

What we claim is:

1. In a lock of the character described, an oscillating latch controlling knob shank, a handle on said knob shank, a cylinder lock 80 within said knob shank including a rotatable plug, a plug extension within said knob shank, a spiral connection between said plug and said extension, a pin carried by said extension and projecting laterally through 85 said knob shank, said knob shank being slotted to permit said pin to be moved to and fro, an escutcheon supporting said knob shank, said pin being arranged to interlock with said escutcheon, means for preventing 90 said plug from being turned in either direction substantially more than one complete revolution, said means comprising a C-shaped member within the shank knob, a stop carried by the knob shank and arranged 95 between the ends of the C-shaped member, a stop shoulder on said C-shaped member and a stop shoulder on said plug arranged to contact with the stop shoulder on said C-shaped member. 100

2. In a lock of the character described, an oscillating latch-controlling knob shank, a spindle secured to the inner end thereof, a handle on the knob shank, a cylinder lock within the knob shank including a rotatable 105 plug, a slot in the side of the knob shank near the inner end thereof, a pin standing in said slot and projecting beyond the side of the shank, a device for carrying said pin arranged within the knob shank, a spiral 110 connection between said pin-carrying device and said plug, an escutcheon surrounding said knob shank outside of said pin, two shoulders forming a pin-receiving recess between them adjacent to the end of said pin 115 whereby when said plug is rotated in one direction said pin will be moved into said recess to lock the knob shank against turning, and when rotated in an opposite direction said pin will be removed from said recess to 120 permit said knob to be turned.

3. In a lock of the character described, an oscillating latch-controlling knob shank, a head on said knob shank, a cylinder lock 125 within said head, a handle carried by said knob shank arranged out of line with said plug, to give free access to the latter, an escutcheon mounted on said knob shank, a longitudinal slot in the side of said knob shank at the rear of said escutcheon, a pin 130

movable in said slot, the outer end of said pin projecting outside of said shank, a carrier for said pin mounted within said knob shank, a spiral connection between said 5 plug and said pin carrier, and a stop shoulder on the back of said escutcheon arranged to block said pin and in turn said knob shank from being oscillated in one direction when said plug has been turned in one direction to 10 move said pin into a position behind said stop.

4. In a lock of the character described, an oscillating latch-controlling knob shank, a head on said knob shank, a cylinder lock 15 within said head, a handle carried by said knob shank arranged out of line with said plug, to give free access to the latter, an escutcheon mounted on said knob shank, a longitudinal slot in the side of said knob 20 shank at the rear of said escutcheon, a pin

movable in said slot, the outer end of said pin projecting outside of said shank, a carrier for said pin mounted within said knob shank, a spiral connection between said plug and said pin carrier, a stop shoulder on the back of said escutcheon arranged to block 25 said pin and in turn said knob shank from being oscillated in one direction when said plug has been turned in one direction to move said pin into a position behind said stop, and a second stop shoulder on the rear 30 of said escutcheon to prevent said pin and said knob shank from being turned in an opposite direction when said pin stands between said stop shoulders.

PHILIP CORBIN.
ERNEST L. TEICH.
